COMBINED LAVATORY AND COUNTERTOP

Howard M. Edgar, Torrance, Calif., assignor to Borg-Warner Corporation, Chicago, Ill., a corporation of Delaware

Filed Apr. 28, 1969, Ser. No. 16,929

Term of patent 14 years

Int. Cl. D23—02

U.S. Cl. D23—58

FIG. 1

FIG.3

FIG. 1 is a top plan view of a combined lavatory and countertop showing my new design;

FIG. 2 is a sectional view taken along line 2—2 of FIG. 1; and

FIG. 3 is a sectional view taken along line 3—3 of FIG. 1.

Portions of the counter top are broken in FIGS. 1 and 2 to indicate indeterminate length.

I claim:

The ornamental design for a combined lavatory and countertop, substantially as shown and described.
